(57) CLAIM

The ornamental design for a handle for kitchen tooling, as shown and described.

DESCRIPTION

FIG. 1 is a front perspective view of the handle for kitchen tooling showing my new design;

FIG. 2 is a front view of the handle for kitchen tooling of FIG. 1;

FIG. 3 is a rear view of the handle for kitchen tooling of FIG. 1;

FIG. 4 is a left side view of the handle for kitchen tooling of FIG. 1;

FIG. 5 is a right side view of the handle for kitchen tooling of FIG. 1;

FIG. 6 is a top plan view of the handle for kitchen tooling of FIG. 1;

FIG. 7 is a bottom plan view of the handle for kitchen tooling of FIG. 1; and,

FIG. 8 is a front perspective view of the handle for kitchen tooling of FIG. 1 with other attached parts shown in broken lines.

The portion shown in broken lines forms no part of the claimed design.
